(57) **CLAIM**

The ornamental design for a support bridge for cameras as shown and described.

DESCRIPTION

FIG. 1 is a front, left, top perspective view illustrating a support bridge for cameras, showing my new design; FIG. 2 is a rear, right, bottom perspective view thereof; FIG. 3 is a top elevational view thereof; FIG. 4 is a rear elevational view thereof; FIG. 5 is a front elevational view thereof; FIG. 6 is a right side elevational view thereof; FIG. 7 is a left side elevational view thereof; FIG. 8 is a bottom elevational view thereof; FIG. 9 is a rear, right, top perspective view thereof; and, FIG. 10 is a front, left, bottom perspective view thereof. The features of the support bridge for cameras shown in broken lines form no part of the claimed design.

1 Claim, 10 Drawing Sheets
